UNITED STATES PATENT OFFICE.

NOAH N. NEHER, OF LOS ANGELES, CALIFORNIA.

VENDING-MACHINE.

1,072,150.

Specification of Letters Patent. Patented Sept. 2, 1913.

Application filed June 24, 1912. Serial No. 705,621.

To all whom it may concern:

Be it known that I, NOAH N. NEHER, a citizen of the United States, residing at Los Angeles, in the county of Los Angeles, 5 State of California, have invented new and useful Improvements in Vending-Machines, of which the following is a specification.

This invention relates to a vending machine for gum or like articles and the prime 10 object thereof is to produce a simply constructed and operated machine capable of delivering to the buyer a package of gum or the like in an efficient manner.

Basically, my invention is comprised in a 15 coin chute which leads to one of four coin pocket members which are rigidly mounted on a central hollow shaft. A turning crank is mounted on a square shaft, this shaft being revolvably mounted in the frame and in 20 side the hollow shaft. A semi-circular shaped member is rigidly attached to the square shaft, and, when the crank is turned, this member comes into contact with the coin. A quarter turn of the crank then au- 25 tomatically delivers the package of gum or like contents to the buyer and drops the coin into the coin box. There are four coin pocket and four delivery mechanisms mounted on the hollow shaft and are held in position 30 by means of a spring, thus, the turning of the shaft, upon which they are mounted, a quarter of a revolution places the following pocket and delivery mechanism in position for the next operation simultaneous with the 35 delivery of the package.

In minor detail my invention also includes 40 many important features, among which is the coin pocket mechanism which is adapted to hold the coin during the quarter revolution of the crank and automatically drop the coin at the same time that the package in the delivery mechanism is delivered to the buyer. I have also provided means for 45 ejecting the money out of the pocket if, for any reason, the coin should get caught in said pocket. The coin pocket is made of such size as to hold a certain coin—say a nickel—and if a smaller coin—say a penny or dime—is inserted in the coin chute, it will 50 not be held by the coin pocket but will drop through to the coin box. A larger coin cannot enter the slot.

I have shown and will describe my invention in connection with gum vending, a 55 preferred form of the same being shown in the accompanying drawings, in which:

Figure 1 is a perspective view of my improved vending machine. Fig. 2 is an enlarged front view with the cover removed. Fig. 3 is a section taken on line 3—3 of Fig. 2. 60 Fig. 4 is a section taken on line 4—4 of Fig. 2. Fig. 5 is a section taken on line 5—5 of Fig. 2. Fig. 6 is a detail showing the coin pocket, with coin therein, in use. Fig. 7 is a section taken on line 7—7 of Fig. 2. 65

In the drawings 10 designates a frame of desired construction which has a portion 11 of some transparent material in the front side. A coin slot 12 and locking member 13 is also mounted on the front side of the case, 70 this construction being typical.

A revoluble square shaft 15 is suitably mounted in the frame, a coin engaging member 16 being rigidly mounted on this shaft, and being revolvably mounted on the hollow 75 shaft 21. This coin engaging member 16 is one of the important features of my invention, as it is adapted to engage with the coin in the coin pocket, and, on the turning of the shaft 15, automatically operate the de- 80 livery mechanism; also, should the coin be caught in the pocket, a portion of the member 16 is cut away so as to allow a square shoulder to drop against the coin and force it into the coin box on the return of the mem- 85 ber 16 to its normal position. The shaft 15 is adapted to be turned a pre-determined distance, through the medium of crank and handle 17^a which is mounted on the outside end of the shaft, and is prevented from 90 turning farther in one direction by portion 16^a coming into contact with part of the coin chute 25, and is held in its normal position, as shown in Fig. 4, by portion 16^b com- 95 ing into contact with the lower end of sta- tionary coin chute 25. A guard 31, on the outside of the case, also prevents any further movement of the shaft and crank. Spring 17 tends to hold the shaft 15 in its normal position through the medium of member 18 100 which is rigidly attached to the shaft 15. The coin chute has a slot 25^a which allows space for the insertion and action of mem- ber 16.

The delivery mechanism 20 is mounted on 105 the outer hollow shaft 21, as is also the coin pocket mechanisms, and is comprised in a delivery wheel as shown in the drawings. A full one quarter revolution of this mechanism 20 delivers to the buyer a package of 110 the contents of the machine; it is held in its normal position, as in Fig. 3, by means of

leaf spring 18^a and member 19, best shown in Fig. 5, which is mounted on the revolving shaft. This spring not only holds the delivery and coin pocket mechanisms in their normal positions, but also accelerates the movement of the same when past the position shown in Fig. 5.

The coin holding pockets 22, four in number, are rigidly mounted on the hollow shaft 21 and are of such size as to receive and hold a pre-determined sized coin, and are also adapted to drop the said coin, by the force of gravity, after the pocket containing said coin has been moved through one quarter of a revolution. This movement is accomplished through the medium of the crank and handle 17^a and member 16. I have also provided a cut away portion, shown at 30 on member 16, for the purpose of ejecting a coin should it happen to be caught in the pocket 22. As best shown in the drawings in Fig. 4, the portion of the member 30 will squarely force the coin out of the pocket on its return to its normal position. The coin box 23 may be of any construction. The upper part of the coin chute 25 is divided into two portions, by means of two cross pieces 26, which prevent any piece of coin from being caught in the chute 30 and also turn the same.

The operation of my device is as follows: A coin is dropped into the slot 12 and falls through chute 25 into one of the coin pockets 22. A movement of the crank 17^a simultaneously moves the member 16 whose end engages with the coin in the pocket 22. A further turn of this shaft engages the coin with the pocket and forces the movement of the same, together with the delivery mechanism. As stated before a quarter turn of these two mechanisms operates the machine, and by force of gravity assisted by leaf spring 18^a the package of gum or other contents drops into the lower part of the case 40 in reach of the buyer and the coin falls into the coin box 23. The crank and member 16 then return to their normal position by virtue of spring 17, and the next coin pocket is then directly below the coin chute 50 and a package of gum or like contents has fallen into the next portion of the delivery wheel. The display and container mechanism 30 may be refilled at any time and the coin removed from the box by merely removing the cover of the case.

It will be seen from the foregoing specification that I have provided a simply constructed and positively operating vending machine of a simple nature.

60 The device can only be operated when a proper pre-determined sized coin is placed in the coin slot, and is adapted to stay there and drop into the coin box at the same time the package is delivered to the buyer.

65 Although I have shown my invention in

the distribution of gum I may add that by changing the size of the delivering mechanism different articles may be vended.

Having described my invention, I claim:

1. A coin controlled apparatus, comprising a central shaft mounted in suitable bearings and having manually operable means for rotation, a hollow shaft rotatable upon the central shaft, a coin pocket member mounted on the hollow shaft and rotatable therewith, said member having a plurality of coin pockets adapted to receive and hold a coin when above the shaft and to discharge it when below the shaft, and a coin engaging member connected with the central shaft comprising two bearing portions one tightly mounted on the central shaft and the other loosely surrounding the hollow shaft, a connecting web between the two bearing portions, and a coin engaging finger projecting from the bearing portion on the hollow shaft. 70 75 80 85

2. A coin controlled apparatus, comprising a central shaft mounted in suitable bearings and having manually operable means for rotation, a hollow shaft rotatable upon the central shaft, a coin pocket member mounted on the hollow shaft and rotatable therewith said member having a plurality of coin pockets adapted to receive and hold a coin when above the shaft and to discharge it when below the shaft, said member comprising two plates oppositely disposed on the hollow shaft and each having lips turned toward the other plate to form said coin pockets, a coin chute leading downwardly to a point above the coin pocket member, the forward wall of the chute being cut away above the coin pocket member and the rear wall extending down between the two opposite plates of said member in front of the hollow shaft, there being an aperture in said rear wall, means to normally and yieldingly hold the coin pocket member with one pocket directly below the chute, and a coin engaging member connected with the central shaft comprising two bearing portions one tightly mounted on the central shaft and the other loosely surrounding the hollow shaft, a connecting web between the two bearing portions, and a coin engaging finger projecting from the bearing portion on the hollow shaft, and adapted to project through the aperture in the rear wall of the coin chute and engage a coin held in one of the coin pockets. 90 95 100 105 110 115 120

3. A coin controlled apparatus, comprising a central square shaft mounted in suitable bearings and having manually operable means for rotation, spring means to hold said shaft in a normal position, means to prevent rearward rotation from the normal position of the shaft, a hollow shaft rotatable upon the square shaft, spring means for normally holding the hollow 125 130

shaft in any one of a plurality of positions, a coin pocket member rigidly attached to the hollow shaft and comprising two oppositely disposed plates affixed to said shaft 5 and having pairs of lips oppositely disposed and turned toward each other to form coin pockets, a coin chute extending downwardly over the coin pocket member with its forward wall terminating above said 10 member and its rear wall extending down between said plate and having an aperture therein, and a coin engaging member comprising a U-shaped portion having one leg rotatively attached to the square shaft be-

yond the end of the hollow shaft and having the other leg loosely surrounding the hollow shaft between the two coin pocket plates, and a curved coin engaging finger projecting from the U-shaped portion and adapted to project through the aperture in 15 the chute rear wall.

In witness that I claim the foregoing I have hereunto subscribed my name this 4th day of June, 1912.

NOAH N. NEHER.
